Patented Apr. 30, 1929.

UNITED STATES PATENT OFFICE.

ROLAND L. STRATFORD, OF CLEVELAND, OHIO.

COMBINED CLOSURE AND IDENTIFICATION DEVICE.

Application filed January 24, 1929. Serial No. 334,657.

The present invention, relating, as indicated, to a combined closure and identification device, is more particularly directed to a new and improved means for the inclusion 5 in a container, such as a sealed bottle, of means adapted to identify the particular beverage contained in the container, and in conjunction with other identifying means in similar containers to permit of the collection 10 of insignia which represent any desired word or name, such for example as the name of the beverage. The general purpose of the invention is the provision of a means for advertising any given beverage and for promoting 15 the use thereof, as will be more fully explained hereinafter.

To the accomplishment of the foregoing and related ends, said invention, then, consists of the means hereinafter fully described 20 and particularly pointed out in the claims; the annexed drawing and the following description setting forth in detail certain structure embodying the invention, such disclosed means constituting, however, but one of various mechanical forms in which the principle 25 of the invention may be used.

In said annexed drawing:

Fig. 1 is a side elevation of a sealed container; Fig. 2 are views in side elevation and 30 perspective of the three elements which when assembled constitute crown or sealing means for the container; Fig. 3 is a view in perspective of one of the elements of Fig. 2; Fig. 4 is a similar view of a sealing washer; Fig. 5 is a view in perspective of the crown proper; Fig. 6 is a transverse central section of a 35 modification of the above device; and Fig. 7 represents the collection of identifying elements when removed from various containers 40 for forming the name of the beverage.

In Fig. 1 I have shown a container in the form of a bottle 1, which may be of glass or other material, bearing on its side the name of the beverage. The bottle is sealed with 45 the ordinary crimped disk or crown 2 which is now in general use for sealing various types of beverage-containing bottles.

The ordinary crown 2 consists of a metal disk and a washer, usually of cork, the washer 50 approximating the size of the top of the bottle and the disk being crimped over the washer and over the top of the bottle, thereby compressing the washer slightly against the rim of the bottle neck and effectively sealing the 55 same until removed.

In Fig. 2 I have shown the crimped crown

or disk 2, the sealing washer 3 and an intermediate disk 4, which may be of metal, paper, cardboard or other material, and on which there is stamped, imprinted or otherwise 60 formed, one of the letters 5 of the name of the beverage, in this case the letter C. Obviously, this identifying letter, number or other indicia, may be placed either on an intermediate element in the form of the disk 65 4, as shown in Figs. 2 and 3, or on the concealed side of the washer 3 or on the lower concealed side 5 of the crown 2, as shown in Figs. 4 and 5, respectively.

By thus marking the various crowns, or 70 supplying with the crowns additional elements or layers carrying various indicia, it is possible to permit users of a given beverage to collect a series of such elements which will 75 spell either the name of the beverage or some given term or phrase, and for which the manufacturer of the beverage may offer either a suitable prize or an additional quantity of the beverage. It will be obvious that numerous variations of this system may be employed, as for example, a given number may be substituted for the name of the beverage, or a given object or figure may be designated 80 which may be built up by a suitable collection of elements concealed within, or attached to, some part of the crown in such a position as to be concealed until the crown has been removed from the bottle.

In Fig. 6 I have shown a further modification, in which there is provided a crown 2 and 90 sealing washer 3 provided on its lower surface with a letter or other indicia 6, which is then covered and concealed by means of a thin disk of foil or other material removably secured to the lower surface of the washer, either by a 95 suitable adhesive or by being of a sufficient size to engage against the upper rim of the bottle when the crown is applied thereto. In this device the indicated symbol is of course concealed until the crown is removed and 100 until the foil or other sheet is in turn removed from the lower surface of the washer.

Other modes of applying the principle of my invention may be employed instead of the one explained, change being made as regards the structure herein disclosed, provided the means stated by any of the following claims or the equivalent of such stated means be employed.

I therefore particularly point out and distinctly claim as my invention:

1. A sealing element for containers con-

sisting of a closure element, having an inner layer of material, said closure being adapted to be snugly fitted about the opening of a container, and said sealing element being provided with indicia on an inner surface in a position concealed until after removal of said closure element from the container and disassembly of said layer of material therefrom.

2. A sealing element for containers consisting of a closure element, having an inner

layer of material, and adapted to be snugly fitted about the opening of a container and provided with indicia on its inner surface in a position concealed until after removal of said closure element from the container and 15 disassembly of said layer of material therefrom.

Signed by me, this 21 day of January, 1929.

ROLAND L. STRATFORD.
